CLAIM

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a rear perspective view of the electronic device shown in a completely unfolded position; and,

FIG. 10 is a top view of the electronic device shown in a completely folded position.

The broken lines shown in the drawings depict portions of the electronic device that form no part of the claimed design. The dot-dash broken lines define boundaries of the claimed design and form no part thereof.
